(57) **CLAIM**

The ornamental design for a bone conduction headphone, as shown and described.

DESCRIPTION

FIG. 1 is a top perspective view of a bone conduction headphone, showing our new design;
 FIG. 2 is bottom perspective view thereof;
 FIG. 3 is a front view thereof;
 FIG. 4 is a rear view thereof;
 FIG. 5 is a left side view thereof;
 FIG. 6 is a right side view thereof;
 FIG. 7 is a top view thereof; and,
 FIG. 8 is a bottom view thereof.

The shade lines in the Figures show contour and not surface ornamentation. The short dash broken lines in the Figures form no part of the claimed design.
